UNITED STATES PATENT OFFICE.

ROSS W. HORNBACK, OF GARDNER, COLORADO.

ROTARY STEAM-ENGINE.

1,311,818.

Specification of Letters Patent.

Patented July 29, 1919.

Application filed February 6, 1918. Serial No. 215,719.

To all whom it may concern:

Be it known that I, Ross W. HORNBACK, a citizen of the United States, residing at Gardner, in the county of Huerfano, State 5 of Colorado, have invented certain new and useful Improvements in Rotary Steam-Engines; and I do hereby declare the following to be a full, clear, and exact description of the invention, such as will enable others 10 skilled in the art to which it appertains to make and use the same.

This invention relates to improvements in steam engines and particularly to rotary steam engines.

15 One object of the present invention is to provide a device of this character which includes novel and improved means for reversing the flow of steam to the cylinder and piston.

20 Another object resides in the provision of a novel and improved sliding abutment for the rotor of the engine.

Other objects and advantages will be apparent from the following description when 25 taken in connection with the accompanying drawing.

In the drawing:

Figure 1 is an elevation of a rotary steam engine made in accordance with my invention.

30 Fig. 2 is an end view of the same.

Fig. 3 is a vertical sectional view taken on the line 3—3 of Fig. 2, showing the valves in one position.

35 Fig. 4 is a similar sectional view showing the position of the valves when reversed.

Referring particularly to the accompanying drawing 10 represents a casing which is formed, internally, with the two diametrically opposite abutments 11 in the inner wall. The inner face of the circular wall of the casing is lined with a packing member 12. Formed on the casing outwardly of the abutments are the valve casings 13 and 14, a passage 15 extending from the abutment inwardly of the casing 13 through the casing, while a passage 16 extends from the other abutment through the casing 14. A rotary valve 17 is mounted in the casing 13, while a similar valve 18 is mounted in the casing 14, the former having a transverse steam passage 19 while the latter is formed with a passage 20. In the top of the casing 13 there is connected a steam pipe 21 which curves upwardly on the external face of the casing 10 and is connected to one

side of the steam chest 22. A similar pipe 23 is connected to the other side of the chest and extends downwardly and is connected to the top of the other casing 14. In the 60 top of the chest there is connected the main steam supply pipe 24. Within the chest is a rotary valve 25 having a recess 26 in the upper side thereof and in the opposite side walls of this recess there are formed the 65 openings 27 and 28, the former of which is adapted to register with the adjacent end of the pipe 21 when the valve 25 is turned in that direction while the other opening is arranged to register with the upper end of 70 the pipe 23 when the valve is turned in the other direction from that first mentioned. Carried by the valve 25 is a pair of radially extending arms 26 which are connected respectively with similar arms 27 carried by 75 the valves 17 and 18, by means of the pivotally connected links 28. A lever 29 is also carried by the valve 25 whereby said valve may be rocked, first into one position and then into the other for the purpose of reversing the direction of rotation of the rotor.

It will thus be seen that when the lever 29 is swung in one direction, one of the valves at the side of the casing 10 will be turned to establish communication between 85 the steam chest and the opening into the adjacent abutment, while when the valve 25 is turned in the opposite direction the first valve will be closed to the steam chest but opened to the atmosphere while the other 90 valve will be opened to the steam chest and other abutment. Thus steam will enter the casing from the second-mentioned valve while the first valve will act as the exhaust. In the first instance, the second valve is the 95 exhaust and the first valve the inlet.

The wheel is composed of the rim member 33, the spokes 34, and the hub 34', the latter receiving the axle or shaft A there-through. Formed longitudinally through 100 two opposite spokes are the bores 32, the outer ends being enlarged to form the recesses 31. Slidably disposed in each of the bores is the stem 35 of the piston 36. Within each recess, and encircling the stem 35, is 105 a coil spring 37, one end bearing against the inner wall of the recess while the other end bears against the rear of the piston. These pistons are thus resiliently held in extended position against the inner face of the casing, 110 as is clearly shown in the drawing, and especially in Figs. 3 and 4. It will be noted

that the bores are longer than the stems whereby free longitudinal movement of the stems is assured.

What is claimed is:

- 5 A rotary engine including a casing having oppositely disposed abutments therein and ports leading therethrough, a rotor mounted in the casing and including a rim and spokes, two of said spokes and the rim 10 being formed with diametrically arranged alining bores, the periphery of the rotor being formed with recesses at the ends of the

bores, pistons movable into and out of the recesses, stems carried by the pistons and 15 slideable through said bores, and springs on the stems within the recesses for normally projecting the pistons outward.

In testimony whereof, I affix my signature in the presence of two witnesses.

ROSS W. HORNBACK.

Witnesses:

GABER PURPHY,
MIKE HALDEZ.
